Application July 25, 1958, Serial No. 51,938

Term of patent 14 years

(Cl. D35—3)

FIG. 5

FIG. 6

Fig. 1 is a front elevational view of a cemetery vase and base unit with the base portion removed and the vase in an upright position, embodying our new design; Fig. 2 is a side elevational view thereof;

Fig. 3 is a top perspective view, on a reduced scale, of the unit in open position showing the vase mounted on the base portion;

Fig. 4 is a top perspective view thereof in closed position, with the vase inverted and placed in the base and the unit rotated approximately 45° from the position shown in Fig. 3;

Fig. 5 is a view similar to Fig. 3, with the vase raised from the base; and

Fig. 6 is an enlarged side elevational view thereof with the unit in closed position.

We claim:

The ornamental design for a cemetery vase and base unit, as shown and described.
